(57) **CLAIM**

The ornamental design for a computer display panel with a transitional graphical user interface, as shown and described.

DESCRIPTION

FIG. 1 is a front view of a first image in a sequence of a computer display panel with a transitional graphical user interface, showing our new design; and, FIG. 2 is a front view of a computer display panel with the second image thereof.

The appearance of the transitional image sequentially transitions between the images shown in FIGS. 1-2. The process or period in which one image transitions to another forms no part of the claimed design.

The outermost broken line illustrates the computer display panel and the remaining broken lines illustrate portions of the transitional graphical user interface. None of the broken lines form part of the claimed design.

The screenshot displays a software application with a clean, modern design. At the top, a navigation bar includes a magnifying glass icon, a user profile icon, and a 'Reports' button. Below the navigation bar, a sidebar on the left contains a 'Return to Dashboard' button, a user profile section with a photo, and a 'Logout' button. The main content area is divided into several sections:

- Financial Summary (1 Application):** A large circular chart showing financial data. The chart has three main segments: 17% (red), 63% (blue), and 20% (green). Below the chart are three buttons: 'OPEN IN BROWSE', 'OPEN IN BIV', and a plus sign icon.
- Property:** A table with columns 'Property Type', 'Current Value', 'Historical Value', and 'Change'. It lists items like 'Residential Properties', 'Commercial Properties', 'Investment Properties', 'Vacancy Status', 'Market Value', 'Previous Value', and 'Appraised Value'.
- Bank Statement:** A table with columns 'Type', 'Amount', 'Description', and 'Status'. It lists items like 'User Type', 'Administrative Type', 'Administrative Related Type', 'User Type', and 'System'.
- Bank Statement:** A table with columns 'Type', 'Amount', 'Description', and 'Status'. It lists items like 'General Interest Rates', 'Interest Expenses', 'Total Interest Expense', 'Interest Rates', 'Total Monthly Expenses', 'Total Monthly Interest Rates', and 'Interest'.
- Bank Statement:** A table with columns 'Type', 'Amount', 'Description', and 'Status'. It lists items like 'Project Name'.
